(57) CLAIM

The ornamental design for a wristband having a gel support member, as shown and described.

DESCRIPTION

FIG. 1 is a front view of a wristband having a gel support member showing my new design; and

FIG. 2 is a rear view of the present invention; and

FIG. 3 is a left side view of the present invention; and

FIG. 4 is a right side view of the present invention; and,
FIG. 5 is a perspective view of the present invention shown in use.

Wherein the dotted lines herein illustrate use and environment only and do not form any part of the claimed design.
